ANTHONY SHAFFER AND ALEXANDER BARCKLEY, OF PHILADELPHIA,
PENNSYLVANIA.

Design No. 2,582, dated February 12, 1867.

DESIGN FOR A COFFEE STRAINER.

The Schedule referred to in these Letters Patent and making part of the same.

TO ALL WHOM IT MAY CONCERN:

Be it known that we, ANTHONY SHAFFER and ALEXANDER BARCKLEY, of the city of Philadelphia, in the State of Pennsylvania, have invented or produced a new and original Design for a Portable Strainer for Coffee and Tea Boilers, of which the following is a full, clear, and exact description, reference being had to the accompanying drawings, making a part of this specification, in which—

Figure 1 is a perspective view; and

Figure 2, a vertical central section of the said strainer—

Like letters of reference indicating the same parts when in both figures.

Portable strainers for coffee and tea boilers are made of either wire gauze or perforated sheet metal, and of a cylindrical form, with flat, or nearly flat, ends. The peculiarity in the shape of our strainer consists in giving to the upper or lid end the form of one end of a hyperbolic conoid.

In the said drawings, A B is the body of the strainer, and C D E the upper end or lid of the same. The exterior form of the body A B is cylindrical, while the lid or upper end C D E is in the form of one end of a hyperbolic conoid, as shown in the drawings.

What we claim as our invention or production, and desire to secure by Letters Patent, is—

The design for a strainer for coffee and tea boilers herein described and shown.

ANTHONY SHAFFER,
ALEXANDER BARCKLEY.
